BOWL AND APRON CONTROL FOR CARRY
TYPE SCRAPERS

William J. Adams, Santa Cruz, Calif., assignor,
by mesne assignments, to General Motors Corporation, Detroit, Mich., a corporation of Delaware

Application August 20, 1949, Serial No. 111,496

4 Claims. (Cl. 37—126)

1

This invention relates to improvements in a power scraper adapted to dig up and carry away large quantities of earth or similar material.

One of the objects of the present invention is to provide a scraper of the type described wherein a scraper blade is provided transversely of the bowl forward of the mid portion thereof so that a portion of the load moves into the bowl rearward of the blade and another portion moves into the bowl forwardly of the cutting blade. Combined with this feature, an ejector comprises the bottom and rear wall of the bowl and is pivoted about a transverse pivot parallel to the cutting blade for tilting of the ejector at a very steep angle for unloading.

Another object of the present invention is to provide a front gate with a very high lift and wherein the front gate and ejector are so constructed and arranged that they nest within each other at their fully raised position so as to obtain the maximum dumping efficiency.

Still another object of the present invention is to provide an ejector having a rear wall which flares upwardly and toward the rear and extending entirely to the top of the bowl giving a wide open top and a rear wall for full loading. My invention also comprises a box beam, an extension wall above the top of the rear portion of the ejector providing for a greater piling of the load at this point and the box beam protecting the ejector against damage when loading by shovel or other overhead equipment.

A further object of the invention is to provide an ejector gate which is moved to such a steep angle during dumping that its center of gravity moves over the ejector pivot, at the same time loading a spring which serves to move the ejector gate center of gravity back over its pivot on the return movement, thus permitting the use of a single acting hydraulic jack or hoist for the ejector dumping movement.

Another feature of my invention is the provision of a telescoping hydraulic jack for use in dumping the ejector arranged in such a manner that the dumping action increases in speed as the load upon the ejector decreases.

A further object of my invention is the connection of a pull yoke between a tractor and the scraper bowl and the mounting of the lifting device for the front apron or gate on the pull yoke whereby the lifting movement of the pull yoke is added to the lifting motion of the front apron actuating device to provide a very high lift for the front apron during dumping.

A further object of my invention is the provision of the lifting device for the scraper bowl on the pull yoke so that a great percentage of the scraper load is transferred to the drive wheels of the tractor.

Still another object of the present invention

2

is to provide novel hydraulic hoist operating means for the bowl and the front gate of the scraper mounted on the pull yoke in a novel manner.

5 A further feature of the present invention is the provision of a novel plural sheave arrangement connected with the hydraulic hoist mounted on the pull yoke so as to multiply the power of the hydraulic hoist as applied to the lifting of the bowl and the lifting of the front apron.

10 A further object of the present invention is a novel arrangement of the lifting hoist and the construction of the pull yoke so as to give the tractor operator a good view of the scraper dumping and loading action.

15 A further object of the present invention is the provision of powerful hydraulic hoists for power and the application of that power by means of flexible cables to the front portion of the scraper bowl and to the front apron of the scraper so as to permit both the bowl and the apron to "float" in a desirable manner without cable interference.

20 A further object of the present invention is to provide a scraper of very strong construction wherein the sides of the scraper bowl, the ejector and the front gate, and the rear frame and pull yoke are of strongly reinforced construction so that the scraper is very sturdy and rugged.

25 A further object of the present invention is the careful selection of the pivot point between the pull yoke and the scraper bowl, taken in conjunction with the position of the digging blade, whereby the digging load on the scraper blade is transferred to the drive wheel of the tractor in a novel and efficient manner.

30 Still another feature of the present invention is the positioning of the hinge connection between the tractor and the scraper in such a fashion that the tractor drive wheel torque load is transferred to the driving wheels of the tractor in a novel manner.

35 A further object of the present invention is the provision of single acting hydraulic hoists for controlling the three separate motions of the scraper together with a simple control valve for each motion mounted on the tractor which gives a very simple and direct operating system and one which is very simple when it comes to locating hydraulic trouble.

40 Other objects and advantages of the present invention will be apparent from the accompanying drawings and description and the essential features thereof will be set forth in the appended claims.

45 In the drawings,
Fig. 1 is a side elevational view of a scraper equipped with my various inventions and showing a rear portion of the tractor which pulls the same;

Fig. 2 is a fragmental top plan view of the scraper of Fig. 1;

Fig. 3 is a longitudinally extending sectional view taken generally along the line 3—3 of Fig. 2;

Fig. 4 is a diagrammatic view illustrating the 5 hydraulic system for operating the various hydraulic hoists;

Fig. 5 is a fragmental sectional view enlarged taken along the line 5—5 of Fig. 1;

Fig. 6 is a diagrammatic view illustrating the 10 reeving of the cables on the hydraulic hoists mounted on the pull yoke and connections of these cables to the scraper bowl and the scraper front apron; while

Figs. 7 and 8 are enlarged diagrammatic views 15 with only pulleys and cables of respectively the bowl hoist and apron hoist construction.

In Figs. 1, 2 and 3, I have shown a scraper bowl 10 comprising two vertically extending parallel side plates 11 rigidly connected together by a box beam construction 12 at the front end, by upper and lower laterally extending box beams 13 and 14 respectively at the rear, and by a 20 triangularly shaped box beam 15 at the mid portion of the bottom of the side walls just to the rear of the cutting blade 16 which is rigidly mounted on the box beam 15. The side plates 11 are entirely flat and unobstructed on their inner side as shown in Figs. 2 and 3. They are reinforced on their outer surfaces by means of the vertically extending channels 17 and 18 and by the horizontally extending channels 19, 20 and 21. These channels numbered 17 to 21 have the free edges of their flanges welded to the outer face of the plate 11 so that the webs of the channels are spaced from and parallel to the plates 11 giving, in effect, box beams at each of these channel connections. Rearwardly of the box beam 15, the bottom of the scraper bowl is provided by the bottom portion 22a of the ejector which is continuously connected by a curved portion with an upwardly and rearwardly flaring back wall portion 22b which is an integral part of the ejector. The ejector is comprised of two parallel plates 23 which are welded to crosswise extending spacers 24 and parallel stiffening ribs 25. The side edges of the ejector which are closely parallel to the inner faces of the scraper bowl side plates 11, are closed by plates 26 which are welded to the plates 23. This gives a very strong construction for the ejector. The ejector is pivotally mounted by the hinge 27 on the top or apex portion of the triangular box beam 15 as clearly shown in Figs. 2 and 3. The box beam 13 may have an extending skirt 13a extending downwardly to substantially meet the upper edge of the ejector portion 22b when the scraper bowl is in its fill position as shown in Fig. 1. To hold a greater load, an extension wall may be provided vertically above the box beam 13 and comprising a vertically extending plate 28 which extends across the entire width of the bowl and which is reinforced by a plurality of parallel ribs 29 which are welded to the plate 28 and to the top of the box beam 13.

The rear support for the scraper bowl is very strongly constructed. Two box beams 30 are rigidly connected as by welding to the rear face of the box beam 13 at points inwardly from the side plates 11 of the bowl. These beams 30 extend rearwardly and downwardly to a bumper 31'. Vertically below each of the beams 30 is a beam 31. These beams are also welded to the rear face of the box beam 14 and extend generally horizontally, tapering inwardly toward 75 the plate 28.

each other to the bumper 31'. The four beams 30, 30, 31 and 31 are welded together to the bumper 31' against which a pusher tractor or bulldozer may exert its pushing effort when aiding the loading of the scraper or moving the scraper forward by additional power. A hook 32 may be provided at this point in case the scraper is used to pull a following vehicle. Approximately midway between the bumper 31' and the rear of the scraper bowl, the beams 30, 30 and 31, 31 are reinforced by means of upper and lower box beams 33 and 34 respectively which are welded between their associated beams, namely, the beam 33 connecting the beams 30, 30 and the beam 34 connecting the beams 31, 31. Two vertically extending box beams 35 at the opposite ends of beams 33 and 34 provide vertical struts. Each beam 35 extends between the beam 30 and the beams 31 on the same side of the vehicle. Stub axles 36 are mounted in the beams 35 and on these are mounted the rear scraper wheels 37. Preferably, a strut 38 is mounted between the mid portion of beam 13 and the mid portion of beam 33 as shown in Figs. 1 and 3. This beam is omitted from Fig. 2 so as to permit the showing of the ejector operating hoist. A beam 38' is positioned under each beam 30 and extends from beam 13 to beam 31.

The support for the scraper at the front end is provided by means of a pull yoke 39 which is connected by means of a hitch 40 with a four wheel tractor, of which two parallel rear wheels 41 are shown mounted on an axle housing 42. It should be understood that this tractor is of the four wheel type having two wheels forwardly of and generally in front-to-rear alignment with the wheels 41 and provided with an engine at the front connected by the usual change speed mechanism and drive mechanism with the axle for driving the wheels 41. The hitch 40 comprises a horizontally extending pivot 43 extending crosswise of the vehicle and mounted on a bracket 44 rigid with the axle housing 42. A bracket 45 which pivots on the pin 43 is connected by a horizontally extending pin 46 with a bifurcated bracket 47. The pin 46 extends in a fore and aft direction. The bracket 47 carries a vertically extending pin 47a which is embraced by a sleeve 48 which is oscillatable about the pin 47a. Rigidly welded to the sleeve 48 are two goose neck shaped I-beams 49 which diverge rearwardly from the sleeve 48 and have their rear ends rigidly welded to a torque tube 50 which extends crosswise of the vehicle. At opposite ends of the torque tube are rigidly welded the yoke arms 51 which extend rearwardly outside of and parallel to the side plates 11 of the scraper. Each of the arms 51 is of hollow box beam construction. The rear end of each arm 51 is pivotally connected by a hinge pin 52 with the scraper bowl. The pins 52 on opposite sides of the bowl are axially aligned. It will be noted that the hinge pin connection 52 of the pull yoke to the scraper bowl is located above and slightly to the rear of the hinge 27 which is just back of the scraper blade 16. It will be noted that the pivot 52 is approximately two-fifths of the distance from the bottom of the bowl to the top and this location has important effects in the practical use of the scraper as will later appear.

The front gate or apron 53 is shown in its closed or lowered position in Fig. 1 and in its 75 upmost raised position in Fig. 3. This gate is

made up of parallel plates 54 between which are welded spacers 55 and reinforcing ribs 56. The plates 54 are welded along their opposite parallel fore and aft extending sides to vertically extending plates 57 which are positioned parallel to and just inside of the side bowl plates 11. At its upper end, each plate 57 is welded to a short cylinder 58 which extends over the side plate 11 of the bowl. To the outside of each of the cylinders 58 is welded an arm 59 which is just on the outside of and parallel to the bowl plate 11. It will be noted that the bowl plates 11 are clear and free of all exterior stiffening ribs at the zone traversed by the arms 59 from the position of Fig. 1 to the position of Fig. 3 so as to permit the location of the arms 59 close to the side plates 11. Each of the arms 59 is pivotally connected by a hinge pin 60 with a bracket 61 which is welded to the reinforcing beam 17 on the side wall of the scraper bowl. It will be noted that there is absolutely no obstruction on the inner face of the front apron 53 or on the inner faces of the ejector portions 22a and 22b. This combined with the smooth inner faces of the bowl side walls 11 comprises a completely clean unobstructed interior wall construction for the scraper bowl. This is very desirable.

A single hydraulic hoist 61 is provided for moving the ejector from the position of Fig. 1 to the dumping position of Fig. 3. This hoist as clearly shown in Fig. 3 comprises a main cylinder 61a, a first piston 61b which moves telescopingly out of the cylinder 61a and a secondary piston 61c which moves telescopingly out of the piston 61b after the latter is fully extended. The cylinder 61a is pivotally mounted at 62 at the central portion of the beam 34. The secondary piston 61c is pivotally mounted at 63 on a suitable bracket on the ejector portion 22b. Pressure fluid is supplied to the cylinder 61a by the hydraulic system shown in Fig. 4 for extending the hoist to move the ejector to the dumping position of Fig. 3. In this manner, as the telescoping pistons 61b and 61c are of increasingly smaller diameter and the fluid supply to the hoist is substantially constant, the ejector moves progressively faster as it dumps the load. This is a single acting hoist and moves the ejector to a position shown in Fig. 3 where the center of gravity of the ejector is forward of a vertical plane through the hinge pivot 27. Two long helical springs 64 are secured between the ejector portion 22b and suitable brackets connected to the side plates 11 just above beams 31 and the ends of beam 14. These springs lie substantially upon beam 14 when the ejector is in the position of Figs. 1 and 2. These springs are sufficiently loaded when the ejector is in the position of Fig. 3 to cause the initial movement of the ejector in a clockwise direction from the position of Fig. 3 when the pressure fluid is released from the cylinder 61a. The springs 64 will return the ejector to the position where its center of gravity is to the rear of a vertical plane through the hinge 27 after which gravity will return the ejector to the position of Fig. 1.

Means is mounted on the pull yoke 39, or more specifically on the torque tube 50 for lifting the scraper bowl and front apron. This means comprises in Fig. 2 parallel spaced hoists 65 and 66 for controlling the scraper bowl and a single hoist 67 located between them and parallel to them for lifting the front apron. Each of these hoists is of similar construction and herefore one only will be explained in detail. For instance, the

hoist 65 in Fig. 2 comprises a cylinder 65a on the near side in Fig. 6 which is closed at its rear end by a plate 65b which in turn is suitably secured by welding or bolting the same to a vertical plane 68 (Figs. 5 and 6) which forms a portion of a sheave housing which is mounted on the torque tube 50 and rigidly welded thereto. The top of this housing is indicated at 69 in the upper right of Fig. 6 and a plurality of vertically extending partition plates 70 are welded to the top 69, to the vertical plate 68 and to the horizontal torque tube 50 providing a very strong construction. Reciprocable in the cylinder 65a on the near side of Fig. 6 is a piston 65c which carries at its front or left hand end a pulley head 65d. Rotatably mounted in the pulley head 65d are two pulleys or sheaves 71 and 72. Rotatably mounted in the vertical partitions 70 of the sheave housing are the rear sheave 73 in fore-and-aft alignment with forward sheave 71 and the rear sheave 74 in alignment with forward sheave 72. The hoist 66 with its cylinder 66a on the far side in Fig. 6 has a similar construction. The pulley head 66d at the upper left has 20 rotatably mounted in it the parallel sheaves 75 and 76. In the sheave housing to the rear the rear sheave 77 at the upper right is aligned with forward sheave 75 at the upper left and the rear sheave 78 is aligned with forward sheave 76 with 25 these rear sheaves 77 and 78 being rotatably mounted between the vertical partitions 70.

A single cable 79 is used on the sheaves of both hoist 65 and 66 for lifting and lowering the bowl. This cable can be described briefly as having one end fixed to torque tube 50, extending around the sheaves on hoist 65 on the near side in Fig. 6 with a bight therein connected with the bowl at 82 at the bottom of Fig. 6, extending in a corresponding manner around the sheaves on hoist 66 on the far side in Fig. 6 with a bight therein connected with the bowl at 87 in Fig. 6, and having its other end also fixed in a corresponding manner to the torque tube 50. This construction is specifically described hereinafter and it should be understood that the left side of Fig. 6 is the front of the hoist mechanism and the right side is the rear. The single cable 79 in Fig. 6 has one end 79a fixed in a dead end wedge socket 80 (Figs. 5 and 6) on the torque tube 50 with said cable extending rearwardly 30 through the plate 68 and bent around a reversing saddle 81 (Figs. 5 and 6) carried by plate 68. The cable then extends around the sheaves on hoist 65 on the near side in Fig. 6 while providing a bight for lifting and lowering the bowl. 35 The cable 79 in Fig. 6 has one end 79a fixed in a dead end wedge socket 80 (Figs. 5 and 6) on the torque tube 50 with said cable extending rearwardly through the plate 68 and bent around a reversing saddle 81 (Figs. 5 and 6) carried by plate 68. The cable then extends around the sheaves on hoist 65 on the near side in Fig. 6 while providing a bight for lifting and lowering the bowl. 40 The cable 79 extends from the reversing saddle 81 along a horizontal lower run 79b extending forwardly (toward the left in Fig. 6) and around the front sheave 71, extends rearwardly along a horizontal upper return run 79c and then over rear sheave 73 to form a downwardly extending moving bight 79d around a lift saddle 82 oscillatably mounted on the box beam 12 at the bottom of Fig. 6 with said beam connected to the front end of the scraper bowl. The cable 79 on the other end of the bight 79d then extends upwardly and around rear sheave 74, extends forwardly as an upper horizontal run 79e and around forward sheave 72, and extends rearwardly as a lower horizontal run 79f and then through plate 68. The cable 79 then extends along torque tube 50 until it is properly aligned with the sheaves of hoist 66 on the far side in Fig. 6. After extending through plate 68, the cable 79 45 coacts with the structure in Figs. 5 and 6 by ex-

tending around a reversing saddle 83 on plate 68, around a cross over saddle 84 fixed on torque tube 50, parallel to torque tube 50, around a second cross over saddle 85 on torque tube 50, and rearwardly around a reversing saddle 86 on plate 68. Then, the cable 79 extends around the sheaves on hoist 66 on the far side in Fig. 6 while providing a bight for lifting and lowering the bowl. After leaving the reversing saddle 86, the cable 79 extends forwardly as a horizontal lower run 79g, extends around forward sheave 75 at the left in Fig. 6, extends rearwardly as a horizontal upper run 79h and over rear sheave 77, and then extends downwardly to produce the moving bight 79i passing around a lift saddle 87 at the bottom of Fig. 6 and fixed to box beam 12 opposite the lift saddle 82. The cable 79 passes from the other end of bight 79i upwardly and over rear sheave 78, extends forwardly as a horizontal upper run 79j over front sheave 76, extends rearwardly as a horizontal lower run 79k, extends rearwardly and around reversing saddle 88 on plate 68, and then extends forwardly and downwardly with its end fixed into another dead end wedge 89' on torque tube 50.

By this arrangement, power strokes of the pistons 65c and 66c forwardly, impelled by pressure fluid, will cause an upward pull on the moving cable bights 79d and 79i causing an upward lift on the lift saddles 82 and 87, thus causing the scraper bowl to rise. Because a single length of cable is used, the action of the hoists 65 and 66 is equalized. Because of the reeving of the cable 79 over the plurality of sheaves just above indicated, the movement of the hoists 65 and 66 is multiplied greatly and gives a high lift to the scraper bowl. In one form of my device, using hoists 65 and 66 having a power travel of not over seventeen inches, I find it possible to drop the scraper blade 16 fourteen inches below the grade line established by wheels 37 and 41 or raise the same to a position twenty-eight inches above this grade line, or a total of forty-two inches of bowl travel in a vertical direction. Because the bowl is hung on the traveling bights 79d and 79i of the cable 79, the scraper bowl is enabled to "float" as the scraper is pulled forward during a digging or dirt spreading operation. This is a valuable feature of cable-operated scraper bowls, but to the best of my knowledge, has never been made possible before using relatively short lengths of cable such as I have provided in the moving bights 79d and 79i. At the same time, I have as much power applied to lifting the bowl as would be found in a known type of cable-operated scraper utilizing a three-drum winch. In my case, the operating mechanism is very much simpler but provides all of the advantages of a floating scraper bowl.

The hoist 67 is mounted parallel to and between the hoists 65 and 66 for the purpose of operating the front apron 53. This hoist consists of a cylinder 67a which is closed at its rear end by the plate 67b which in turn is bolted to the plate 68. A piston 67c is reciprocatable in the cylinder 67a by means of pressure fluid supplied to the rear end of the cylinder. The free end of the piston carries the head 67d in which are rotatably mounted three sheaves in parallel relationship, namely, 89, 90 and 91. Aligned with these in the sheave housing are the respective sheaves 92, 93 and 94 which are rotatably mounted in the partition plates 70. A cable 95 has one end 95a secured firmly at a dead end wedge socket 96 which is secured in the sheave

housing. A run of the cable 95b then extends forwardly and around the pulley 89, then run 95c extends rearwardly and around pulley or sheave 92, then run 95d extends forwardly around sheave 90, then run 95e extends rearwardly and around sheave 93, then run 95f extends forwardly and around sheave 91, then run 95g extends rearwardly and around sheave 94, after which the free end of cable 95 extends downwardly as indicated at 95h and is secured to an eye of a bracket 96' located on the lower mid central portion of the front apron 53. It results from this construction, that when the piston 67c makes a power stroke forwardly impelled by pressure fluid admitted to the rear end of the cylinder 67a, the sheaves 89, 90 and 91 are carried forwardly causing a pull on the cable 95 which raises the apron 53 from the closed position of Fig. 1 to the open position of Fig. 3. It will be obvious from a study of Figs. 1 and 3 that the movement of the front apron 53 along with the cable 95 is in equal increments during the first half of the movement of the apron upwardly because the cable 95 lies flat against the front face of the apron 53 during this portion of apron movement. After the bracket 96' passes the point of tangency with the cable 95 indicated at 97 in Fig. 3, as the bracket 96' moves upwardly from the point 91, a given increment of lengthwise movement of the cable 95 causes a greater increment of front apron movement while the cable 95 is moving from a position of tangency to the path of the bracket 96' to a position almost radially of this path of movement. For instance, as viewed in Fig. 3, the cable portion 95h is almost in line between the top of pulley 94 and the pivot point 60 about which the front apron moves. Thus, as the apron moves upwardly its speed increases although the power applied to it will decrease slightly. This is in accordance with the necessities of the case because the load on the apron is less as it reaches its raised position.

The above described apparatus for operating the front apron 53, has an advantage similar to that described in connection with the scraper bowl, namely, that the front apron floats on the relatively short length of cable 95h while the scraper is being filled but without any great length of cable to become snarled up. At the same time, the multiplication of movement through the plurality of sheaves operated by the hoist 67 gives a great deal of cable travel for the operation of the front apron.

The hydraulic system for operating the various hydraulic hoists heretofore described is shown diagrammatically in Fig. 4. The ejector hoist cylinder 61a is connected by line 98, with valve 99 mounted on the tractor body. The two hoists 65a and 66a have their cylinders connected by lines 100 and 101 respectively with line 102 which leads to control valve 103 on the tractor body. The apron hoist 67a has its cylinder connected by line 104 with control valve 105 on the tractor body. These valves are located in a position where they may be operated by valve operating handles 99a, 103a and 105a respectively located alongside the driver's seat 106 on the tractor. This is a very simple hydraulic system and one which is easy to keep in efficient operation. Each of the hoists is single acting. As mentioned previously, the springs 64 cause the initial return movement of the ejector from its raised position after which gravity causes the pistons 61b and 67c to return into the cylinder

61a. Obviously, the scraper bowl 12 moves downwardly under the action of gravity and the front apron 53 also returns from raised position to its lower or closed position under the action of gravity. This system makes it very easy to determine where leakages occur. For instance, if the scraper bowl tends to drift downwardly, if there is a leak in the hoist the oil will be leaking out of it and it will be simple to locate the trouble. If not, the only other place that this trouble could occur would be in the valve 103 so that the mechanic would immediately know where to go to work. Similar considerations apply to the ejector hoist and the front apron control hoist. It will be noted also that only 15 three flexible hoses, namely, 92, 102 and 104, are necessary between the tractor and the trailer. By mounting the valves and their control levers on the tractor, it is possible to arrange the control levers so that they are very convenient for 20 the tractor driver to operate them.

The operation of my improved scraper should now be obvious. With the tractor moving forwardly, the operator actuates valve 103 to remove all pressure fluid from the hoists 65 and 66, thus allowing the scraper bowl to drift downwardly until the blade 16 digs into the earth. At the same time, the operator actuates valve 105 to operate hoist 67 to open the front apron 53 sufficiently to operate the scraper bowl to fill 30 as desired. As the bowl fills, the operator will eventually release all pressure fluid from the hoist 67 allowing the apron 53 to "float" until it reaches the closed position of Fig. 1. Depending upon the type of digging, the operator may lift the scraper bowl as it fills, or he may lift it after it becomes completely filled. In any case, eventually the operator actuates the hoists 65 and 66 to cause the scraper bowl to be lifted to the carrying position of Fig. 1. The operator 40 then runs the tractor to the desired location, after which he operates the hoist 67 to lift the front apron 53 and actuates the valve 99 to send pressure fluid to cylinder 61a so as to move the ejector from the position of Fig. 1 to the position of Fig. 3 to dump the load. Usually, during such a dumping operation the tractor and scraper are moved forward so as to distribute the load in the desired manner. After the load is dumped, pressure is removed from the ejector cylinder 61a, permitting the ejector to return to its position in Fig. 1 and generally also closes the front apron 53 so as to move the scraper back to its original position again.

One of the advantages of my improved scraper is that the mounting of the three hoists 65, 66 and 67 on the top of the pull yoke or draw bar helps throw the dead weight of the scraper forward, getting more of the scraper weight on the tractor drive wheels. In an actual test where the total tractor weight was 18,200 pounds and the scraper weight (unloaded) was 22,300 pounds, there was a slightly greater load on the drive wheels 41 than on the rear scraper wheels 37 in the unloaded condition. When this equipment was loaded with 42,000 pounds of earth, the actual weight on the driving tires 41 was 35,505 pounds and the actual weight upon the rear wheels 37 of the scraper was 36,000 pounds. This will be recognized by those skilled in the art as a very exceptional distribution of the weight and one which is very favorable to a high traction on the rear wheels of the tractor.

As has been mentioned previously, in this same embodiment of my invention, it is possible to ob-

tain forty-two inches of vertical travel of the bowl which is very important when an operator has to lift himself out of trouble as when the equipment has so much material piled up in front of it that it cannot move. The bottom of the front apron 53 in the position of Fig. 3 is about six feet from cutting edge 16. This helps when dumping a large mass of sticky soil.

Referring to Fig. 3, it will be noted that there is a space indicated by the dimension A between the lower side of the three hoists 65, 66 and 67 and the top of the torque tube 50. In an actual embodiment, this dimension A is about six inches and gives a clear vision of the operator, sitting on the seat of the tractor, toward the rear. This is very important if the operator is to watch the loading of the scraper and if he is to watch a pushing tractor acting upon the bumper 31'. The plate is cut away at its mid portion as indicated at 68' to give clearer vision.

Another feature of my scraper is the open top of the scraper bowl. It will be noted that this is unencumbered by any beams, pulleys, projections or obstructions of any sort and this is very advantageous if the scraper is loaded by means of a shovel.

The position of the cutting blade 16 is such that the reaction of the digging or scraping operation rearwardly on the blade 16 is transferred, because of the proper location of the pivot 52, in an economical manner to cause a downward load on drive tires 41. This greatly aids in the loading action of the scraper and particularly when there is very little dirt loaded into the scraper bowl. In other words, at the beginning of the digging action, the drive wheels 41 are loaded just when the load is most needed.

Referring to Fig. 1, it will be noted that the pin 43 which is the pivotal connection between the scraper and the tractor is located forwardly of a plane B extending through the axis of the axle housing 42 on which the drive wheels 41 are mounted. It is well known that when a tractor is trying to pull and unable to make progress, the front end of the tractor tends to rear. In other words, there would be a tendency for the pivot 43 to tend to move in the direction of the arrow of Fig. 1. It will be obvious that this movement is impossible because the entire load of the front portion of the scraper is acting downwardly at this point and must be lifted before the tractor can rear. This torque load transfer of the tractor drive wheels provides more tractive effort for loading power in the combination of the tractor and the scraper.

It will be noted also that the scraper has an extremely low over-all height and extremely low center of gravity. This gives a very good stability of the scraper either empty or loaded. The scraper is very rugged and sturdy and of extreme simplicity and closely coupled to the tractor in front of it. Added to all this is a positive, fast and quickly responsive control of the working actions of the various operations of the scraper parts as described in connection with the description of the operation of my invention.

What I claim is:

1. In a digging and carrying scraper and a tractor for moving the same, including a scraper bowl having side walls and a bottom and an open front end and means for closing the same, including wheel means supporting the rear end of said bowl, including a drawbar having a pivotal connection between its rear end and said bowl, and including a hitch connection between

the front end of said drawbar and said tractor; the combination therewith of a hoist having relatively movable cylinder and piston members reciprocable in a fore-and-aft path, one of said hoist members being fixed on said drawbar, the other of said hoist members being movable forwardly therefrom, sheave means carried by said movable hoist member, sheave means positioned in rear of said fixed hoist member, a cable fixed at one end to said drawbar and reeved over both said sheave means to provide a movable run of said cable, with said cable extending beyond the fixed sheave means to form a connection with the forward end of said bowl.

2. In a digging and carrying scraper and a tractor for moving the same, including a scraper bowl having side walls and a bottom and an open front end and means for closing the same, including wheel means supporting the rear end of said bowl, including a drawbar having a pivotal connection between its rear end and said bowl, and including a hitch connection between the front end of said drawbar and said tractor; the combination therewith of two spaced parallel hoists, each hoist having relatively movable cylinder and piston members, each hoist having one of its members fixed on said drawbar and having its other member reciprocable forwardly therefrom, a head carried by each said movable hoist member, two sheaves rotatably mounted in each movable head, a fixed head positioned in rear of each fixed hoist member, two sheaves rotatably mounted in each fixed head and in fore-and-aft alignment with the movable head sheaves of the associated hoist, the axes of all of said sheaves being at right angles to the direction of hoist reciprocation, a single cable having one end fixed and then reeved on one hoist by passing around a first front sheave and around a first rear sheave and then downward and upward to provide a moving bight and then over a second rear sheave and forward around a second front sheave and then having a cross-over run to the other hoist and being reeved on said other hoist by passing around a first front sheave and around a first rear sheave and then downward and upward to provide a moving bight and then over a second rear sheave and forward around a second front sheave and then to a device for fixing the other end of said cable, and spaced fixtures near the forward end of said bowl about which said moving bights pass.

3. In a digging and carrying scraper and a tractor for moving the same, including a scraper bowl having side walls and a bottom and an open front end, including an apron for closing said front end and having a pivotal mounting on said bowl for movement between a closed and an open position, including wheel means supporting the rear end of said bowl, including a drawbar having a pivotal connection between its rear end and said bowl, and including a hitch connection between the front end of said drawbar and said tractor; the combination therewith of three hoists mounted in parallel relation on said drawbar, each of said hoists having relatively movable cylinder and piston members, each of said hoists having its fixed member mounted on said drawbar and having its movable member reciprocable forwardly therefrom, a plurality of rotatable sheaves carried by each hoist movable member, a plurality of rotatable sheaves mounted in rear of each hoist fixed member in fore-and-aft

alignment with the sheaves of the movable member of the associated hoist, the axes of all of said sheaves extending at right angles to the direction of hoist reciprocation, a cable reeved over the sheaves associated with the middle hoist of said three parallel hoists and having a moving run of said cable connected with said apron to raise and lower the same, and a second cable reeved over the sheaves associated with the two outer hoists of said three hoists and having an equalizing run extending across said middle hoist position to equalize the action of said two outer hoists on said second cable, said second cable having a moving run connected with the forward portion of said bowl.

4. In a digging and carrying scraper including a scraper bowl having side walls and a bottom and an open front end and means for closing the same, including a frame supporting said bowl and having a frame portion above and in front of the front end of said bowl, and including wheel means supporting said frame; the combination therewith of two parallel hoists mounted on said frame portion, each of said hoists having a relatively movable cylinder and piston members reciprocable in a fore-and-aft path, each of said hoists having one of its associated hoist members fixed on said frame portion and the other of its hoist members being movable forwardly therefrom, fixed pulley means at the rear end of each of said hoists, movable pulley means carried by each of said movable hoist members, a single length of flexible cable having its opposite ends fixed relative to said frame portion, said cable being reeved over said pulley means associated with both of said hoists and providing two movable bights each passing downwardly and around an idler pulley mounted on the front end of the said bowl, whereby a lift of multiplied mechanical advantage is provided at all times substantially vertically upward to the front end of said bowl and said bowl floats on said bights of said cable and the lifting action of said two hoists is equalized through said cable.
